J. H. Gibbs, of Albany, N. Y.

Assignor to

Evan Packus, of Sleepy Hollow, N. Y.

Letters Patent No. 1077, dated Jan. 11, 1859.

The schedule referred to in these Letters Patent and making part of the same.

To all whom it may concern:

Be it known that I, J. H. Gibbs, in the City of Albany, in the County of Albany and the State of New York, have invented or produced a new and original ornamental design for a parlor Franklin Stove, and I do hereby declare that the following is a full and exact description of the same, reference being had to the accompanying drawings and to the letters of reference marked thereon,

I claim as original all ornaments running along the outer edge of the top A, also the ornaments B, placed around the center and on the flat surface of the top A, also ornaments forming center C, and handle E, the whole forming in combination, the ornamental top, of the said Franklin Stove,

All ornaments placed on the Front F, and, marked respectively C, also the ornaments forming the Band H, which crosses the Front, the whole, forming in combination an ornamental Front plate of the said Franklin Stove,

Also all ornaments M, placed on the plate immediately above and resting on the band H, forming in combination an ornamental ^WBlower of the said Franklin Stove, all ornaments placed on the plate marked J, together with the ornaments around the base of said plate, marked K, the whole forming in combination an ornamental ashpit cover or plate of said Franklin Stove.

All ornaments running around the outer edge or molding of the bottom I, forming in combination the ornamental bottom plate, of said Franklin Stove, the whole of the said ornamental plates forming in combination an ornamental Parlor Franklin Stove as shown in the accompanying drawings.

What I claim as original, and desire to secure by letters patent, is the combination of ornaments and ornamental configuration of the different plates of Parlor Franklin Stoves, as described and set forth in the accompanying drawings.
